APPAREL FASTENER

Robert Ellis, Belleville, N. J.

Application March 27, 1943, Serial No. 480,749

2 Claims. (Cl. 2-96)

This invention relates to apparel fasteners and the principal object of the invention is to enable the flaps of a garment to be secured to each other by means of permanent magnets in lieu of buttons or other customary mechanical fastenings.

Another object of the invention is to enable the flaps of a garment to be more quickly and conveniently fastened or unfastened than is now possible by other means.

A still further object of the invention is to enable a garment to be secured around the body of a wearer with an elastic fit if desired.

A still further object of the invention is to provide a magnetic fastener which will enable the wearer to conveniently and quickly secure the garment around the body to any adjustable degree of tightness desired.

Yet another object of the invention is to provide a garment fastening means which is entirely invisible either when the flaps of the garment are closed or open.

Other and further objects will appear in the specifications and will be specifically pointed out in the appended claims, reference being had to the accompanying drawings exemplifying the invention, and in which:

Fig. 1 is a top view of an article of apparel showing the flaps thereof closed and secured by my magnetic fastener.

Fig. 2 is a front view of Fig. 1 with the flaps in open position.

Fig. 2A is a front view similar to Fig. 2 but illustrating a modification thereof.

Fig. 3 is a similar view to Fig. 1 with a slight modification thereof.

Fig. 4 is a side view of a pair of permanent magnets with the legs or pole pieces thereof in corrugated or serrated form for exerting greater attractive force with each other.

Fig. 5 is a similar view to Fig. 2, illustrating a modification thereof.

Fig. 6 is a top view of Fig. 5 showing the flaps secured and the article of apparel closed.

Fig. 7 illustrates how a magnetic fastener would be used to close the opening of a pocket.

Fig. 8 illustrates how my magnetic fastener would be used on a garter, belt or similar article.

Fig. 9 shows the two ends of a garter and how the magnetic fastener is arranged to operate same.

Fig. 10 is a cross sectional view on the line F—F of Fig. 11.

Fig. 11 illustrates a method of securing a garment and incidentally providing an elastic fit thereto.

Figs. 12 and 13 illustrate a variation of magnet structure especially applicable to apparel closures where considerable tensional strain is encountered in the wearing thereof.

Fig. 14 shows a cross sectional view of a magnetic button secured to the garment flaps.

Fig. 15 illustrates the magnetic button of Fig. 14 and its armature in front view.

Fig. 16 is a cross sectional view of a modified form of magnetic button secured to the garment flaps.

Fig. 17 illustrates a still further modification of my magnetic button especially adapted to be used with garments of light weight fabric.

Referring more particularly to the drawings in which similar numerals and character of reference refer to similar parts throughout the several views, the numerals 11A and 11B denote the usual two associated cloth flaps of a garment which are usually drawn together about the body of a wearer and then secured in such closed position by means of buttons or other fastening means. In lieu of buttons or other fastening means as now customarily used, I employ permanent magnets 12A and 12B, sewed, glued, riveted or otherwise satisfactorily attached to each flap 11A and 11B respectively, the inherent magnetism remanent in these permanent magnets causing them to forcibly hold together when once contacted and to resist separation as will be readily understood, thus securely holding the flaps of the garment in closed position similar to any other fastening means, much less effort and time being required in such closing operation. The same is true when it is desired to open the garment, it being merely necessary to force the flaps apart by inserting a finger therebetween and forcing the finger downwards which is sufficiently effective in overcoming the magnetic attraction between the permanent magnets.

So as not to interfere with the natural flexibility of the garment, the permanent magnets 12A and 12B are composed of thin flexible sheet steel strips and each having a comparatively large number of magnetic pole-pieces 13 protruding from a common yoke 14 as illustrated in Figs. 2 and 7. Each pole-piece 13 is of course of opposite magnetic polarity to its adjoining pole-piece of the same magnet and the magnets 12A and 12B are so secured to the flaps 11A and 11B respectively that, when the flaps overlap each other at the correct place for closing the garment as better illustrated in Fig. 1, the opposite pole-pieces of each magnet will be in alignment but all the "north" magnetic poles of magnet 12A will con-

tact all the "south" magnetic poles of magnet 12B, as indicated by the letters N and S respectively in Fig. 1. The same arrangement of opposite magnetic pole-pieces contacting each other is to be taken for granted in all the illustrations herein showing U-shaped magnets. The permanent magnet strips are sewed to the cloth flaps of the garment by means of thread stitches 20 passing through the holes 15 or are glued or riveted to the cloth flaps. If desired, the upper and lower pole-piece of each magnet 12A may be provided with a snap fastener 16A formed directly out of the thin metal magnet by punching while the co-acting receptive part of the snap fastener, 16B is formed in the same manner in the pole-piece of magnet 12B, thus providing additional closure security. Instead of having two permanent magnets attached to opposite flaps as heretofore described, one of the flaps may be provided with an unmagnetized flexible iron armature 17 composed of a number of fine wires or screen and sewed to the flap 11B, this arrangement being illustrated in the lower right hand corner of Fig. 2. It will be noted that, due to the large number of pole pieces 13 and their close juxtaposition, as compared to buttons, the garment flaps will be held together very closely along their edges without much possibility of wind or weather entering therebetween.

Modifications of the above are illustrated in Fig. 3 in which the permanent magnets 12A and 12B are composed of a plurality of very thin laminated strips and covered with a thin cloth lining 18A and 18B respectively, the lining rendering the magnets invisible yet being sufficiently thin to permit the magnetism to penetrate therethrough and secure the flaps in place with almost the same attractive force as that arrangement illustrated in Fig. 1. The laminated magnets have the double advantage of greater flexibility and greater remanence per cross sectional area as compared to a single strip. In Fig. 4 is shown a still further modification which is designed to increase the tractive force of the permanent magnets with each other, the pole pieces 13 herein being corrugated so as to snugly fit into each other, it being readily understood that an opposite pull on the magnets would tend to lift parts of the corrugations from each other, such actual separation of any part being resisted by tractive force whereas, when a simple sliding action occurs along the face of the magnet, considerably less magnetic force is evident. Besides, the magnetic force holding these corrugated or serrated pole pieces together will insure greater mechanical friction against separation due to the angular travel of the pole pieces when a straight pull is exerted. However, when used to close pocket flaps as illustrated in Fig. 7, the heavy line 19 denoting the opening, the pole pieces 13 are forcibly separated at right angles to the magnetic faces and away from each other, necessitating greater effort than where a longitudinal sliding motion is used. Of course the magnets 12A and 12B in the pocket 19 are invisible as shown by the dotted lines. It will also be noticed that the magnetic closures illustrated in Figs. 1, 2 and 3 are both flexible and adjustable, that is, the flap 11B may be folded over flap 11A to a more or less extent, determined by the length of the pole pieces 13, the magnetic attraction then holding the flaps in that set position, thus enabling the wearer to adjust the tightness of the garment about the body to suit his desires. Should unusual tensional strain be applied to the

flaps 11A and 11B, such as by heavy breathing, bending the body, etc., the pole pieces will resistively slide on each other from their original set position to a place of equilibrium strain existing between the now lessened tension and the still forceful magnetic attraction of the permanent magnets, this arrangement providing for greater wearing comfort than where the flaps are definitely secured by a purely mechanical contrivance without providing any elasticity.

A row of individual magnets 21A and 21B may also be used on each flap as illustrated in Figs. 5 and 6 and in which the permanent magnets are preferably moulded within thin disks 22 of plastic material, thus resembling buttons in appearance and which may be sewed to the flap by thread in the usual manner through holes 23, or fastened in any other way most applicable.

Another application of my magnetic fastener is illustrated in Figs. 8 and 9 in which the numeral 24 denotes either an elastic band such as would be used for a garter, or a non-elastic band such as would be used for a belt, one of the ends in either case being provided with a thin flexible armature 25 while to the other end is attached a number of permanent magnets 26, preferably in the shape of thin steel bars and having their magnetic poles opposite each other as indicated by the letters N and S. It will thus be apparent that the band 24 may be used to very conveniently and quickly encircle an object, one end being merely laid over the other end whereby fastening thereof is immediately secured through the magnetic attraction of the permanent magnets 26 for the armature 25, the armature closing the magnetic circuit between the north and south pole pieces and thus forming a strong tractive force. Besides, owing to the multiplicity of the spaced bar magnets 26, adjustability as to size of the object surrounded is simultaneously secured as well as "give" to a certain extent if too great a tensional strain is applied, yet permitting the magnets to retain hold of the armature in such new position. Both the armature 25 and the bar magnets 26 may be sewed directly to the band 24 or first attached to a cloth strip 27 which in turn may be more effectively sewn to the band 24 as indicated by the stitches 28. It will be evident that either a garter or a belt equipped with this apparel fastener can be applied to and removed from the wearer with a minimum amount of effort and time and incidentally provides adjustability as to length.

Figs. 10 and 11 show a method of applying an elastic fit to a garment, the flaps 11A and 11B being each provided with a plurality of permanent magnets 12AA and 12BB respectively, similar to the construction illustrated in Figs. 1 and 2. However, in this case, each magnet 12BB is free to move within the pocket formed in the flap 11B by the stitches 29, the elastic band 30, which is secured around the yoke of the magnet 12BB, normally holding the magnet in the position illustrated in Fig. 11, while when in use, the magnet may be held in the position illustrated in Fig. 10 and cause the elastic band 30 to stretch, especially when the wearer breathes heavily, stoops over, etc. The other end of the elastic band 30 is sewed onto the flap 11B by the stitches 31. It will be understood that the magnetic attraction will permeate through the space utilized by the cloth flaps which are here shown covering both sides of the magnets.

Fig. 12 illustrates a face view of two co-operating permanent magnets while Fig. 13 is a section

on the line G—G of Fig. 12. It is well known that the transverse sliding friction of two magnetic elements in contact has much less resistance than the traction or direct pulling away from each other and as it is in many applications inconvenient to apply direct magnetic tractive force to my apparel fastener without making such closure device too conspicuous and cumbersome, I provide means whereby the tendency to sliding of the magnets due to unusual tension is prevented by a simple mechanical lock, the pole pieces providing the tractive force necessary to hold the locking means in position. In this case, the pole pieces 13A have punched in them a number of tongues 32 which extend downward as illustrated in Fig. 13 while permanent magnet 12B is provided with correspondingly spaced holes 33 so that when the magnet 12B is placed underneath magnet 12A, the tongues 32 will enter the holes 33 and the magnetic attraction of the pole pieces will prevent their disengagement except by forcible means. Of course it is understood that this arrangement may be used with any kind of garment or apparel attached thereto.

Figs. 14 and 15 illustrate still another application of my invention and in which I provide a magnetic button 34 in the shape of a thin circular disk of material such as plastic which is glued or sewed to the front face of the garment flap 11B, a circular permanent magnet disk 35 being fitted into the lower portion of the disk 34, held thereto either by friction or glue, this lower portion of the disk 34 being preferably "sunk" into the garment flap by cutting out a corresponding hole so as to provide a flush face to the garment front as shown in Fig. 14. For greater magnetic holding power, the magnet 35 is provided with both a north and south pole piece on its outer face by means of the annular groove 36, there being also holes 37 so as to enable the button to be sewed onto the garment if preferred, by means of stitches 38. Associated with permanent magnet 35 attached to flap 11B is the soft iron disk armature 39 attached to flap 11A, which disk may also be sewed to the garment by means of the holes 40 and stitches 41. This disk armature 39 is sufficiently small to enable it to easily fit into the round hole 42 left by the space between the upper face of the permanent magnet 35 and the annular rim on the outside of the plastic disk 34, so that when the garment flap 11A is pressed against flap 11B and the armature 39 fitted into hole 42, the magnetic attraction between permanent magnet 35 and armature 39 will cause them to be held in such position and, due to the recess provided by hole 42 and the inwardly inclined sides of hole 42, the disk cannot be dislodged through any tension applied to the flaps customary while wearing but, in case it is desired to remove the garment from the body of the wearer, the flap 11A is simply pulled outwards with sufficient force to overcome the magnetic traction holding armature 39 to magnet 35 whereby the disk is easily pulled out of hole 42. It will here be noted that the use of this magnetic button will permit a garment to be more conveniently put on and taken off than by means of the conventional button and button-hole as this magnetic button can be easily manipulated while wearing gloves, in case fingers are numb through cold, in difficult places of access, by young children, etc., while the appearance of the garment is enhanced by the elimination of buttons and button-holes, inci-

dentally giving to the garment a clean cut streamlined appearance.

Fig. 16 illustrates a similar view to Fig. 14 and shows the magnetic button 35 sewed to the outside face of flap 11B and without any embellishing plastic holder. In this case however, the armature disk 39 is held from sliding movement across the face of magnet 34 by means of the depression created by having the central or north magnetic pole piece of less height than its encircling annular south magnetic pole piece, the armature disk 39 easily fitting into this depression and held thereon by magnetic attraction, the annular shoulder on the inner side of the south magnetic pole piece preventing sliding off.

In Fig. 17 is disclosed a slight variation from the magnetic buttons of Figs. 14 and 16, in this case the button being especially adapted for apparel made of thin cloth such as is generally used for shirts, dresses, etc. The armature of soft sheet iron stamping 34A is sewed or attached to the outside of flap 11B, this armature having an annular depression 42A into which the disk 39A loosely fits when the flap 11A, to which the disk is sewed, is folded over flap 11B. The disk 39A is sewed to flap 11A through the medium of the two holes 40 which are connected by a shallow trough 43 into which the threads used in sewing on the button are designed to lay so as not to form a protuberance and prevent the face of the disk 39A to lay flat against the bottom face of the hole 42A for better magnetic contact and neater appearance. In this case, the disk 39A is permanently magnetized, this being easily accomplished even with such a thin piece of steel or alloy, the outer face being assumed to be the north pole piece while the inner face, against the cloth flap 11A, will be the south pole piece. With this magnetic button also, the magnetic attraction holds the two parts of the button together while the annular shoulder of hole 42A prevents sliding apart.

Of course it will be understood that the apparel fastener herein disclosed may be used on various forms of apparel such as coats, shirts, pockets, trousers, garters, belts, shoes, etc., as well as for numerous other applications outside of the garment line such as tent flaps, automobile tops, wallets, handbags, etc.

From the foregoing description, it will be evident that I have evolved an apparel fastener which has many advantages over others now in use as it can be made absolutely invisible either when the garment is open or closed; its use is more convenient when either closing or opening the garment flaps; it is more quickly manipulated; it is adjustable to a considerable degree as the permanent magnets will hold the garment flaps at any originally set position; it is elastic in that not only will the magnets slide on each other under an excessive strain but elastic material may be conveniently associated between the magnets and the garment; it is flexible in that the permanent magnets may be made of such thin spring steel that they will flex along with the garment while in use; it can be constructed to be of neat and varied appearance; and incidentally will resist as much tensional strain as any mechanical fastener as the magnetic qualities of my fastener are so designed to provide mechanical locking for same; besides, when used with pockets will automatically close the flaps when the hand is withdrawn; can be produced as cheap and cheaper in many respects as other apparel fasteners; and will eliminate all

button-holes and present a neat clean cut appearance to the garment.

Various changes may be made in the embodiment of the invention hereinabove specifically described without departing from or sacrificing the advantages of the invention as defined in the appended claims.

I claim:

1. An apparel closure comprising two oppositely disposed flexible flaps of an article of wearing apparel, one or more permanent magnets attached to the margin of one of said flaps,

and a plurality of armatures attached to the margin of the opposite flap, said armatures consisting of substantially thin flexible magnetically attractive wires or strips arranged parallel to said margin of said opposite flap and slightly separated from each other.

2. An apparel closure as in claim 1, said separated flexible armature wires or strips being attached to said flap so as to be invisible from the outer side of said article of apparel.

ROBERT ELLIS.
